[57] CLAIM

The ornamental design for a light attachment for the end of a cane or umbrella, substantially as shown and described.

DESCRIPTION

FIG. 1 is a top perspective view of a light attachment with the light bulb in upright illuminated position showing my new design;

FIG. 2 is a first side elevational view thereof;

FIG. 3 is a second side elevational view thereof;

FIG. 4 is a third side elevational view thereof showing the light bulb in inverted unilluminated position;

FIG. 5 is a fourth side elevational view thereof;

FIG. 6 is a top plan view thereof;

FIG. 7 is a bottom plan view thereof;

FIG. 8 is a top perspective view of a second embodiment of my new design with the light bulb in upright illuminated position;

FIG. 9 is a first side elevational view thereof;

FIG. 10 is a second side elevational view thereof;

FIG. 11 is a third side elevational view thereof with the light bulb in inverted unilluminated position;

FIG. 12 is a fourth side elevational view thereof;

FIG. 13 is a top plan view thereof; and

FIG. 14 is a bottom plan view thereof.
